DRIER AND OVERLAPPER

Robert J. Thompson, Harrisburg, Pa.

Application May 31, 1938, Serial No. 210,945

12 Claims. (Cl. 271—76)

This invention is an apparatus for drying sheets of paper or the like.

One of the objects of the invention is to provide a rotatable drier drum having means for independently supporting the sheets during transition through a drying space. A further object is to provide means for successively directing the individual sheets into and removing them from the rotatable drier drum without interruption to the rotative movement thereof, and in a manner to avoid development of static electricity. A further object is to provide a drier drum of the type mentioned provided with a plurality of radially disposed belts so constructed and arranged as to draw the sheets into sector-like chambers within the drying space, and then to cause each sheet to move from one side of its chamber to the other side thereof during the rotative travel of the drum D.

20 The invention will be hereinafter fully set forth and particularly pointed out in the claims.

In the accompanying drawings:

Figure 1 is a side elevation illustrating a drying apparatus constructed in accordance with the invention, parts being shown broken away. Figure 2 is a detail view illustrating the driving mechanism. To avoid possible confusion in the illustration, this driving mechanism has been omitted from Figure 1.

30 Figure 3 is an enlarged detail sectional view on line 3—3, Figure 1.

Figure 4 is a horizontal sectional view of the drier drum looking downwardly.

Figure 5 is a fragmentary side elevation illustrating a modification of the take-off mechanism.

Figure 6 is a top plan view of Figure 4.

Referring to Figures 1, 2 and 3 of the drawings, D designates a drier drum comprising two laterally spaced side plates 10, 11, secured to a shaft 40 12 in such manner as to rotate therewith. Shaft 12 is rotatively mounted in suitably supported bearings 13, and is rotated by any desired type of power drive, a pulley 14 to receive a driving belt 14^a being shown for purposes of illustration.

45 Extending transversely between the side plates 10 and 11, at positions adjacent to the drive shaft 12 is a series of rotatably mounted belt-rollers 15. Said rollers are arranged in a circle concentric with said shaft 12. A second circular series 50 of rotatable belt-rollers 16 is mounted between the side plates 10 and 11 near the peripheries thereof, being also arranged concentrically with said drive shaft 12. Each roller 16 is provided at one end with a drive pinion 17 constructed for any preferred type of gearing, a friction type of

gearing having been selected for illustrative purposes.

The same number of belt-rollers 15 and 16 is employed and said rollers are so disposed as to provide a plurality of pairs of rotatable belt supports, each pair consisting of a rotatable member 15 and a rotatable member 16. By means of this arrangement each pair of belt rollers provides support means for a radially disposed endless belt which may be of any desired construction, 10 said belts providing sheet-receiving pockets P between them. However, to reduce the possibility of creating static electricity by friction, it is preferred to construct each belt of a plurality of axially spaced endless cords 18 passed around 15 each pair of rollers in such manner that rotative movement of said rollers 15 and 16 in the same direction will impart traveling movement to the cords.

The dampened sheets S which are to be dried 20 are individually and successively deposited (by means not shown) upon an endless feed belt 19, mounted upon rotatable supports 20 which may be actuated by any well known mechanism, such for instance as a pulley or sprocket wheel a 25 driven by sprocket chain b receiving power from a suitable source, not shown. On the same shaft as wheel a and rotating therewith is a second pulley or sprocket wheel c, connected by a belt or chain d with and driving a larger pulley or sprocket wheel e located on the opposite side of the drum D. Located adjacent to the delivery end of the feed belt 19 is a vertically disposed feed actuator device in the form of a movable endless belt 21 carried by rotatable supports 22, 30 mounted in the frame of the apparatus in a manner not shown. Said belt 21 is so positioned that it will be successively engaged by the rollers 17 as the drum rotates, so that rotative movements are imparted to members 16 during such engagement. 35

On the opposite side of the drum D is an endless take-off belt 23, mounted on suitable rollers 24, and actuated by the pulley or sprocket wheel e. Adjacent to the receiving end of belt 23 is a take-off actuator consisting of a movable endless belt 24 carried by supports 25, which are mounted on the frame of the apparatus in identically the same manner as described for belt 21. Cooperating with belt 23 is a guide device or "overlapper" 26 of any desired form for directing the dried 50 sheets downwardly to the top of said belt, as they leave the drum D.

In practice, the interior of the drum is heated by any means well known in the art and, as shown, is rotated in an anti-clockwise direction 55

by belt 14^a, although the parts may be constructed to travel in the opposite direction without departing from the spirit of the invention. At the same time movement toward the drum D is imparted to the feeder belt 19 and movement away from the drum D is imparted to the take-off belt 23. The ratio of pulley or sprocket wheel e with respect to pulley or sprocket wheel a is such that the belt 23 is driven at a slower speed than belt 19. This ratio may be varied as desired without departing from the spirit of the invention, a ratio of 3 to 1 being shown for purposes of illustration.

In operation, the sheets S are successively deposited on the top of belt 19 and carried thereby to the drum D, the feed of sheets being so regulated as to allow belt 19 to advance the sheets to the successively presented openings between the belts 18. As a belt 18 approaches the delivery end of belt 19, the latter projects the forward end of the sheets S onto the uppermost stretch of said belt 18. Just previous to this movement travel of the belt 18 toward the center of the drum D has been initiated by engagement of roller 17 with the feed actuator 21, so that as the projected sheet engages the belt 18, the latter while moving upwardly, carries the sheet which rests upon the upper stretch thereof, toward the center of the drum. By the time the roller 17 has passed beyond the feed-actuator 21 the entire sheet will have been deposited upon the belt 18, and said sheet will continue to rest upon said belt until the latter passes the dead center, whereupon the force of gravity will cause the sheet to fall over and rest against the under side of the preceding belt 18, which is reversing its position as it is carried around with the drum. As each belt 18 approaches the location of the take-off device 23, its roller 17 will engage the take-off actuator 24 so as to impart outward movement to said belt 18. This movement causes the reversed sheet S to travel outwardly toward belt 23. The overlapper 26 will catch the forward end of the delivered sheet as it leaves the belt 18, and hold the same upon the belt 23, so that the latter will impart continued outward travel to the said sheet. As the pockets P continue their travel past belt 23, the rear end of each sheet is carried past the receiving end of said belt, so that said rear end is left depending from said receiving end of belt 23, during part of the time that the delivered sheet is traveling with said belt. Before each delivered sheet S has been moved to a position entirely upon the belt 23, the next succeeding sheet is delivered to said belt and caught by the overlapper in the manner already described, so that the last delivered sheet is held in superposed position upon but with its rear end back of the rear end of the previous sheet. Therefore, each succeeding sheet is laid upon the top of the immediately preceding sheet but in overlapped relation, and so held by the overlapper 26 as to practically prevent rubbing or sliding of the sheets upon each other, thereby avoiding generation of static electricity. The foregoing describes the movements imparted to each successive sheet presented by belt 19.

The modification illustrated in Figures 5 and 6 differs from the other form in the substitution of a rigid cam-like feed-actuator and a rigid cam-like take-off actuator for the belts 21 and 24. Inasmuch as they are identical in structure, it is considered sufficient to describe

one of them, and the take-off device has been selected for purposes of illustration.

Referring to Figures 5 and 6, a rigid curved track 30 is supported by a bracket 31 fixedly secured to the frame F. The functions and operation are identically the same as those already set forth in connection with the previously described structure.

The advantages of the invention will be readily appreciated by those skilled in the art to which it belongs. For instance, it will be readily observed that a very simple and effective drum-type drier is provided, by means of which each sheet of material to be dried may be individually fed to the drum, and so supported as to have both surfaces thereof effectively exposed to the drying temperature. Another important advantage is that the feeding and other handling of the sheets is accomplished in such manner as to prevent rubbing of the sheets upon each other or upon other surfaces, so that development of static electricity is practically prevented. In other words, the overlapper in conjunction with the sheet drier has many advantages. The sheets are laid on top of each other. They are not slid over the top. In this way there is no static created. Also, by lapping the sheets they are slowed down on the overlapper to about one-fourth (1/4) of the speed of the sheet when entering the drier. By slowing the sheets down to this much reduced speed, there will be less trouble at the delivery end.

It is to be understood that although the use of invention has been specifically described with respect to the drying of paper sheets, it is not limited thereto, but is equally applicable to the drying of any other sheet material.

Having thus explained the nature of the invention and described an operative manner of constructing and using the same, although without attempting to set forth all of the forms in which it may be made, or all of the forms of its use, what is claimed is:

1. A sheet-feeding device of the character described comprising a rotatable drum having a plurality of radially disposed sheet supporting devices, means for loosely positioning individual sheets of material upon successively presented sheet supporting devices during rotative travel of the drum, and means for periodically actuating said sheet supporting devices in such manner as to eject each sheet from the drum by a positive radial movement away from the center of the drum.

2. A sheet-feeding device of the character described comprising a rotatable drum having a plurality of radially disposed sheet supporting devices, means for loosely depositing individual sheets of material upon successively presented sheet supporting devices during rotative travel of the drum, means for periodically actuating said sheet supporting devices in such manner as to move each sheet inwardly toward the center of the drum by a positive radial movement, and means for periodically actuating said sheet supporting devices in such manner as to eject each sheet from the drum by a positive radial movement away from the center of the drum.

3. A sheet-feeding device of the character described comprising a rotatable drum, radially disposed movably mounted endless sheet supports mounted in said drum, feed means for loosely depositing individual sheets of material upon successively presented sheet supports, periodically operated means for actuating said sheet sup-

ports as they move past said feed means so as to positively move each sheet inwardly toward the center of the drum, and periodically operated means for effecting removal of each sheet from the drum at a position opposite the feed means by a positive outward radial movement.

4. A sheet-feeding device of the character described comprising a rotatable drum, radially disposed movably mounted endless sheet supports mounted in said drum, feed means for loosely depositing individual sheets of material upon successively presented sheet supports, periodically operated means for actuating said sheet supports as they move past said feed means so as to positively move each sheet inwardly toward the center of the drum, and periodically operated means for again actuating said sheet supports in such manner as to successively withdraw the sheets from the drum by a positive outward movement.

5. A sheet-feeding device of the character described comprising a rotatable drum, having a plurality of sheet supports consisting of a pair of rotatable members and radially disposed endless sheet supports carried thereby, feed means for loosely depositing individual sheets of material into said drum in such manner as to deposit them upon successively presented sheet supports, means for imparting periodical rotation to one rotatable member of each sheet support as it passes the location of said feed means, so as to positively move each sheet into the drum during rotative movement of the latter, and means for again imparting rotation to said rotatable member in such manner as to successively withdraw the sheet from the drum by a positive outward movement.

6. A sheet-feeding device of the character described comprising a rotatable drum, having a plurality of sheet carriers consisting of a pair of rotatable members and radially disposed endless sheet supports carried thereby, feed means for projecting individual sheets of material into said drum in such manner as to deposit them upon successively presented sheet supports, a roller carried by one rotatable member of each feed device, a stationary feed actuator positioned adjacent to said feed means and in the path of movement of and engageable with said rollers, so as to impart rotation to said rotatable member while passing the location of said feed means in such manner as to positively move each sheet into said drum, and means for again imparting rotation to said rotatable member in such manner as to successively withdraw the sheet from the drum by a positive outward movement.

7. A sheet-feeding device of the character described comprising a rotatable drum, having a plurality of sheet carriers consisting of a pair of rotatable members and radially disposed endless sheet supports carried thereby, feed means for projecting individual sheets of material into said drum in such manner as to deposit them upon successively presented sheet supports, a roller carried by one rotatable member of each feed device, a stationary feed actuator positioned adjacent to said feed means and in the path of movement of and engageable with said rollers, so as to impart rotation to said rotatable member while passing the location of said feed means in such manner as to positively move each sheet into said drum, and a stationary take-off actuator also located in the path of and engageable with said rollers in such manner as to cause the

successive sheet supports to positively eject the sheets from said drum.

8. A sheet-feeding device of the character described comprising a rotatable drum, having a plurality of sheet carriers consisting of a pair of rotatable members and radially disposed endless sheet supports carried thereby, feed means for projecting individual sheets of material into said drum in such manner as to deposit them upon successively presented sheet supports, a roller carried by one rotatable member of each feed device, a movable flexible endless belt member positioned adjacent to said feed means and in the path of movement of said rollers, so as to impart travelling movements to the sheet supports as they successively pass said feeding means, so as to positively move each sheet into the drum, a similar movable flexible belt member also located in the path of and engageable with said rollers, in such manner as to cause the successive sheet supports to positively eject the sheets from said drum, and means for actuating said flexible belts.

9. A sheet-feeding device of the character described comprising a rotatable drum, having a plurality of sheet carriers consisting of a pair of rotatable members and radially disposed endless sheet supports carried thereby, feed means for projecting individual sheets of material into said drum in such manner as to deposit them upon successively presented sheet supports, a roller carried by one rotatable member of each feed device, a rigid cam-like member fixedly supported at a position adjacent to said feed means and in the path of movement of said rollers, so as to impart travelling movements to the sheet supports as they successively pass said feeding means, so as to positively move each sheet into the drum, and a similar rigid cam-like member also located in the path of and engageable with said rollers, in such manner as to cause the successive sheet supports to positively eject the sheets from said drum.

10. A sheet-feeding device of the character described comprising a rotatable drum having a plurality of radially disposed sheet supporting devices, means for periodically loosely depositing individual sheets of material upon successively presented sheet supporting devices, means for periodically actuating said sheet supporting devices in such manner as to eject each sheet from the drum by a positive radial movement away from the center of the drum, means for receiving the ejected sheets in superposed relation, and means for preventing relative slidable movement of the superposed sheets as they are ejected.

11. A sheet-feeding device of the character described comprising a rotatable drum having a plurality of radially disposed sheet supporting devices, a feed device for loosely depositing individual sheets of material upon successively presented sheet supporting devices, a sheet receiving member operable at a slower speed than the feed device, means for periodically actuating the sheet supporting devices in such manner as to eject each sheet from the drum onto the sheet receiving member by a positive radial movement away from the center of the drum, and means for preventing relative slidable movement of the ejected sheets while upon said sheet receiving member.

12. A sheet-feeding device of the character described comprising a rotatable drum having a plurality of radially disposed sheet supporting devices, a feed belt adapted to loosely deposit

- individual sheets of material upon successively presented sheet supporting devices, a traveling sheet receiving device moving at a slower speed than the movement of the feeding device, means for periodically actuating said sheet supporting devices in a manner to eject the respective sheets from the drum onto said sheet receiving device

in superposed relation and by a positive radial movement away from the center of the drum and in such manner that the rear end of each sheet will depend from the sheet receiving device, and means for preventing relative slidable movement of the superposed sheets.

ROBERT J. THOMPSON.
